UNITED STATES PATENT OFFICE.

FREDERICK B. COLE, OF LONGBEACH, CALIFORNIA.

CONCRETE-SHINGLE MOLD.

1,075,403.

Specification of Letters Patent. Patented Oct. 14, 1913.

Application filed January 23, 1913. Serial No. 743,827.

To all whom it may concern:

Be it known that I, FREDERICK B. COLE, a citizen of the United States, residing at Longbeach, in the county of Los Angeles and State of California, have invented certain new and useful Improvements in Concrete-Shingle Molds; and I do declare the following to be a full, clear, and exact description of the invention, such as will enable others skilled in the art to which it appertains to make and use the same.

This invention relates to improvements in concrete shingle molds.

One object of the invention is to provide a shingle mold by means of which shingles may be formed directly on a roof and in separate or independent courses thus providing for the contraction and expansion of the shingles without injuring the roof structure or cracking the shingles.

Another object is to provide a mold of this character whereby the successive independent courses of shingles may be formed without waiting for the previously laid courses to set or harden.

With these and other objects in view, the invention consists of certain novel features of construction and the combination and arrangement of parts as will be more fully described and claimed.

In the accompanying drawings; Figure 1 is a perspective view of a portion of a roof showing the manner in which the shingles are formed thereon by my improved mold; Fig. 2 is a similar view illustrating on one portion of the roof the finished courses of shingles and on the other portion of the roof illustrating the molds still in position thereon; Fig. 3 is an enlarged vertical sectional view of a portion of a roof illustrating the operation of forming the shingles thereon with my improved mold; Fig. 4 is a top plan view of a portion of one of the shingle forming boards of the mold; Fig. 5 is an edge view thereof; Fig. 6 is a detail perspective view of one of the fastening rods for the shingles.

My improved shingle mold comprises a board or plate 1 of suitable width and length, the width of the board 1 being slightly greater than the length of the exposed parts of the shingles formed thereby. On the upper side of the board 1 are secured transverse cleats 2 which are of less length than the width of the boards and which terminate at the upper ends thereof a short

distance from the upper edges of the boards as clearly shown in Figs. 3 and 4 of the drawing. The cleats 2 when thus arranged form stops to support the boards when arranged for forming the successive courses of shingles.

Secured to the lower side of the board 1 are a series of crease forming strips 3 which are spaced equal distances apart, the spaces 65 between the strips corresponding to the width of the shingles. The strips 3 are of slightly less length than the width of the boards 1 and terminate above the lower edges of the boards a distance corresponding 70 with the distance the boards overlap each other when arranged for forming the successive courses of shingles as clearly shown in Fig. 3 of the drawings.

In forming a roof and covering the same with my improved shingles the sheathing boards 4 are laid on the rafters in the usual manner and along the lower edge of the lowermost sheathing board is laid a spacing strip 5 to which is secured a narrow strip 6 80 for forming the lower end of the lowermost course of shingles and which supports the lower edge of the mold board 1 for the first course of shingles as clearly indicated in Fig. 3 of the drawings. After the strips 5 and 6 have been temporarily secured to the rafters at the lower edge of the sheathing boards 4 the latter are covered with the usual or any suitable form of tar or waterproof paper or felt 7. Arranged at intervals on the paper 7 a suitable distance above the lower edge of the roof or above the bottom strip 6 are a series of V-shaped shingle fastening rods 8 the upper looped ends of which are fastened by staples 9 or other suitable fastening devices to the sheathing boards 4 as clearly shown in Figs. 1 and 3 of the drawings. After the lower course of rods 8 have thus been arranged and secured, the cement or concrete for forming the lower 100 course 10 of shingles is placed on the waterproof paper along the lower portion of the roof and is troweled down from the strip 6 to the desired thickness or taper as shown. After the cement for the lower course 10 of shingles has thus been placed on the roof and troweled out one of the mold boards 1 is laid on the lower portion of the cement, said board having its lower edge resting on the upper edge of the bottom strip 6. When 110 thus arranged the lower ends of the crease forming strips 3 on the lower side of the

board 1 engage or abut against the upper side of the bottom strip 6 and thus hold the board in proper position for forming the upper surface of the first course of shingles 5 and the lower end of the next course. When the board 1 is thus placed on the cement the strips 3 are forced down or will embed themselves into the upper surface of the cement and will form creases which will imitate the 10 usual crack or space which occurs between the wooden shingles of the roof. After the lower course of shingles have thus been formed a strip of tar or water-proof paper 11 is laid over the tapered upper portion 15 of the cement forming the first course of shingles and which is exposed above the upper edge of the board 1. After this sheet of tar paper 11 has been placed in position another set of the shingle holding rods 8 20 are arranged over the paper and secured at their upper ends to the sheathing boards 4 in the same manner as described in connection with the lower series of fastening rods. After the sheet of paper 11 and the second 25 series of rods 8 have been arranged in position, the cement for the second course of shingles 12, is placed on the paper and over the rods and is troweled down from the upper edge of the board 1 to the desired thickness 30 and taper after which a second board 1 is placed on the lower portion of the cement forming the second course 12, the lower edge of this board resting on the upper portion of the board forming the preceding course of shingles. When thus arranged the crease forming strips of the second board have their lower ends engaged 35 with the upper edge of the board forming the first course of shingles, the lower edge 40 of the board forming the second course of shingles engages the upper ends of the cleats 2 on the upper side of the preceding board and is thus supported and held in proper position for forming the top of the 45 second course of shingles and the bottom or lower end of the next course. The succeeding courses are formed in the same manner as the second course and a further description of the formation of the successive 50 courses of shingles is not thought to be necessary.

In thus forming the shingles it will be noted that each successive course is entirely separate or independent from the other 55 courses and that in thus forming the courses they will be permitted to expand and contract to any extent without injuring any part of the structural framework of the roof or cracking the shingles. By providing the 60 fastening rods 8 it will be seen that the courses of shingles are also secured to the sheathing boards of the roof so that said courses have absolutely no connection with

each other except the loose overlapping engagement of the lower portions thereof, said overlapping portions being separated by the sheets of tar or water-proof paper arranged between the same while the courses are being formed. It will also be noted that in constructing the roof in the manner described, the successive courses of shingles may be formed before the preceding courses have set or hardened and without danger of the cement of one course becoming mixed with or joining the cement of the preceding course 75 thereby permitting the construction of the shingles to be rapidly and easily accomplished.

From the foregoing description taken in connection with the accompanying drawings 80 the construction and operation of the invention will be readily understood without requiring a more extended explanation.

Various changes in the form, proportion and the minor details of construction may be 85 resorted to without departing from the principle or sacrificing any of the advantages of the invention as claimed.

Having thus described my invention, what I claim is:

1. In a shingle forming mold of the character described, the combination of a series of mold boards adapted to be placed one above the other in overlapping engagement, a plurality of cleats secured to the upper 95 surface of said boards and adapted to limit their overlapping engagement, a series of creasing members secured to the lower surface of said boards to form creases in the shingles, and means to separate the successive courses of shingles thereby permitting 100 said courses to be formed before the preceding courses have set or hardened.

2. A shingle forming mold of the character described comprising a series of boards 105 having on their upper sides cleats adapted to form supports for the boards of the successive molds, creasing strips secured to the lower sides of said boards and adapted to form creases in the shingles to represent 110 cracks between the shingles, means to separate the courses of shingles formed by one of the mold boards from the courses formed by the preceding boards, and shingle fastening rods adapted to be secured at their upper ends to the roof and to be embedded in the courses of shingles when the latter are formed thereby independently fastening the courses of shingles to the roof.

In testimony whereof I have hereunto set 120 my hand in presence of two subscribing witnesses.

FREDERICK B. COLE.
